CONSTRUCTION OF RUGS OF PILE FABRICS

Filed Aug. 29, 1934

FIG. I.

FIG. II.

FIG. III.

FIG. IV.

FIG. V.

INVENTOR:

CHARLES HERBERT DAVISON,

BY *Arthur E. Faig*
Attorney.

UNITED STATES PATENT OFFICE

2,001,381

CONSTRUCTION OF RUGS OF PILE FABRICS

Charles Herbert Davison, Princeton, N. J.

Application August 29, 1934, Serial No. 741,978

7 Claims. (Cl. 28—1)

My invention provides a method of and means for binding cut edges of pile fabric to prevent raveling of the pile tufts and other elements of the fabric at such cut edges. Although my invention may be employed with particular advantage in connection with Axminster rugs and carpets, it is not limited to such embodiments but is applicable to pile fabrics of any kind.

It is the present trade practice to charge \$1.27 $\frac{1}{2}$ per yard for binding the cut edge of an Axminster fabric by a method and means which are standard practice in the trade and which consist in allowing one and one-half inches extra length of the fabric at any edge which is to be bound, plucking the pile tufts from that inch and a half length and the full width of the fabric, binding the cut edge by the use of a sewing machine which overcasts the cut edge to an extent of about one-half inch with a coarse thread in stitches resembling those used for forming buttonholes, then bending the plucked portion of the fabric backing backward upon and parallel with the face of the fabric opposite to the tufts, and hemming it to the body of the fabric by a line of machine stitches intermediate of the width of the overcasting. Obviously such a method of procedure is wasteful of the pile material of the fabric and laborious and consequently costly. Moreover, the edge of a fabric thus finished does not lie flat upon a plane surface but is upheld by the thick portion thereof turned under and, consequently, such raised edge of the fabric is subjected to greater wear than the body of the fabric and becomes threadbare.

Therefore, it is the object and effect of my invention to not only minimize the waste, labor and cost of binding a cut edge of a pile fabric but also to permit the cut edge, when bound, to lie flat upon a plane surface and thus avoid the extraordinary wear incident to the ordinary construction aforesaid.

As hereinafter described, it is characteristic of my invention that binding warps of the fabric, which are extended beyond the body of the fabric for only about one-half inch, are bent backward upon the face of the fabric opposite to the pile so as to tightly bind in the fabric the wefts adjoining the cut edge, and are tightly secured on the back of the fabric by an elastic cement and covered by a flat band of thin tough material, for instance, a closely woven textile tape about one inch wide, which is also secured to the back of the fabric parallel with the plane 55 of the latter by an elastic cement with one edge

of said band coextensive with the bights of said bent back binding warps, so that the fabric thus bound will lie flat upon a plane surface.

My invention includes the various novel features of construction, arrangement, and method of procedure hereinafter more definitely specified.

Fig. I is an elevation of a portion of the longitudinal edge of an Axminster pile fabric having the cut edge thereof which is at the right in said figure bound in accordance with my invention.

Fig. II is an inverted plan view of an Axminster pile fabric designed to be severed transversely at intervals throughout its length to form rugs to be bound in accordance with this invention, showing the binding warps securing the backing wefts, with the wefts omitted for a space of one inch between adjoining sections of the pile structure to afford the desired extension of the binding warps when the fabric is severed between said sections.

Fig. III is a longitudinal edge view of the section shown at the left of Fig. II and with the binding warps extending from the backing.

Fig. IV is a perspective view of the back of the fabric indicated in Fig. III with the extended binding warps bent back upon the face of the fabric opposite to the pile and secured by elastic cement.

Fig. V is a perspective view of the back of the fabric shown in Fig. I with the binding in accordance with this invention completed.

Referring to Fig. I the backing 1 of the fabric has the pile tufts 2 looped therein only to the region 4, where the binding warp threads 3 are bent backward to the extent indicated at 9 and are covered by the thin tough binding band 10, the right hand edge of which is coextensive with the bights of said warps 3 and the construction is such that the fabric thus bound will lie substantially flat upon a plane surface.

As indicated in Fig. II, the binding warps 3 are arranged in pairs in laterally spaced relation to bind the three series of backing wefts 12, 13, 45 and 14. Said wefts 14 are not visible from the back of the fabric but are held upon the front face thereof by said binding warps 3 and engage the bights of the tufts 2 which are held between said wefts 14 and the wefts 12 and 13. As shown in Fig. II, all of the wefts are omitted at 15 for a space of about one inch in the length of the fabric between adjoining sections of the pile provided portions of the fabric. Such sections are severed transversely with respect to the 55

fabric along the line 16 leaving the binding warps 8 projecting about one-half inch from the edge of the backing 1, as indicated in Figs. III and IV. Thereupon, a coating 18 of elastic adhesive 5 is applied to the backing 1 upon the face opposite to the pile 2 and said normally extending ends of the warps 8 are bent backward and pressed upon the backing 1, as indicated at 19 in Fig. IV, so as to tightly secure them in position to securely bind the end wefts in the backing 1.

Thereupon, a second coating 20 of the elastic adhesive is applied over the bent back ends of the warps 8 and of such extent as to secure 15 the flat binding band 10 when the latter is pressed thereon, as indicated in Fig. V. I also prefer to apply a third coating 21 of said adhesive upon the bent bights of said warps 8 and the edge of said band 10, as indicated in Fig. 20 V. to further secure the same together.

Although any suitable adhesive may be employed in the manner above specified, I have found it convenient to employ a mixture of approximately three parts of what is known to 25 the trade as "filler paste", to wit, a paste formed of flour of grain such as rye boiled in water, mixed with approximately one part of rubber cement, i. e., liquid Pará gum of the consistency of commercial liquid glue; the mixture 30 forming the preferable elastic adhesive aforesaid, being of that consistency when applied, but capable of setting as quickly as animal glue or grain paste.

However, it is to be understood that I do 35 not desire to limit myself to the precise details of construction, arrangement or method of procedure above set forth, as it is obvious that various modifications may be made therein without departing from the essential features of 40 my invention, as defined in the appended claims.

I claim:

1. The method of forming rugs of Axminster pile fabric which consists in weaving said fabric with successive areas thereof provided with pile, 45 and with spaces between said areas devoid of pile; the adjoining areas being connected solely by binding warps; severing said fabric intermediate of said spaces devoid of pile; bending back the severed ends of the binding elements 50 upon the back of the fabric opposite to the pile and securing said ends by elastic adhesive so that the end wefts of the fabric are thus bound in the fabric; and covering said bent back ends with a flat band of tough material 55 extending along said edge coextensive with the bights of the bent back binding warps and secured by said adhesive.

2. An Axminster pile fabric rug structure including three series of backing wefts, two series

of binder warps interwoven with all of said wefts, and pile warps forming tufts having their bights engaged with one series of said wefts; wherein ends of the binder warps are extended beyond a transverse edge of the fabric and bent back beneath it under said wefts, and parallel with said warps; a coating of elastic adhesive on the back of said fabric securing said warp ends thereto; a second coating of elastic adhesive covering said binder warp 10 ends; and a flat band of tough material extending along said edge, at the back of the fabric, parallel with said wefts, covering said warp ends and secured by said adhesive.

3. An Axminster pile fabric rug structure including three series of backing wefts, two series of binder warps interwoven with all of said wefts, and pile warps forming tufts having their bights engaged with one series of said wefts; wherein ends of the binder warps are extended 20 beyond a transverse edge of the fabric and bent back beneath it under said wefts, and parallel with said warps; a coating of elastic adhesive on the back of said fabric securing said warp ends thereto; a second coating of elastic adhesive 25 covering said binder warp ends; and a flat band of tough material extending along said edge, at the back of the fabric, parallel with said wefts, covering said warp ends and secured by said adhesive; and a third coating of elastic adhesive 30 on the bights of said bent warp ends and adjoining edge of said band.

4. A structure as in claim 2, wherein the elastic adhesive includes the dried residue of liquefied rubber.

5. A structure as in claim 2, wherein the elastic adhesive includes the dried residue of liquefied rubber mixed with the dried residue of an aqueous paste of grain flour.

6. A structure as in claim 2, wherein the band 40 is a closely woven textile tape having selvages at its opposite longitudinal edges.

7. The method of forming rugs of pile fabric which consists in weaving said fabric with successive areas thereof provided with pile, and 45 with spaces between said areas devoid of pile; the adjoining areas being connected solely by binding warps; severing said fabric intermediate of said spaces devoid of pile; bending back the severed ends of the binding warps upon the 50 back of the fabric opposite to the pile and securing said ends by adhesive so that the end wefts of the fabric are thus bound in the fabric; and covering said bent-back ends with a flat band of tough material extending along said 55 edge, and secured by said adhesive.

CHARLES HERBERT DAVISON.
